UNITED STATES PATENT OFFICE.

LYMAN O. PICKETT, OF BINGHAMTON, NEW YORK.

PROCESS OF MAKING TAR-FELT MATERIAL.

1,321,669.

Specification of Letters Patent. Patented Nov. 11, 1919.

No Drawing.

Application filed May 23, 1918. Serial No. 236,217.

To all whom it may concern:

Be it known that I, LYMAN O. PICKETT, a citizen of the United States, residing at Binghamton, in the county of Broome, State of New York, have invented a new and useful Process of Making Tar-Felt Material; and I do hereby declare the following to be a full, clear, and exact description of the invention, such as will enable others skilled in the art to which it appertains to make and use the same.

The present invention relates to a process of making tar felt material, and has for its object to provide an inexpensive and expeditious method whereby a tar felt sheet suitable for use between shoe soles, as roofing, or the like, can be readily produced.

Further objects of the invention are to provide a process for producing the tar felt sheet material which insures a proper mixing of the ingredients and enables the mixed product to be rolled into sheets of the desired thickness without sticking to the rolls.

In carrying out the invention a quantity of binding material such as tar, asphalt or rosin is placed in a container and subjected to a sufficient amount of heat to convert it into a liquid form. A fibrous filling substance such as tannery hair, scrap felt, or comminuted rags and paper is then placed directly into the melted tar and the tar and fibrous material stirred until they are thoroughly mixed, the fibrous material being completely saturated with the tar, and a sufficient quantity of fibrous material being used to absorb practically all of the tar. The hot semi-liquid mixture is next removed from the container and cooled by subjecting it to a water bath. This application of cold water prevents the mixture from becoming sticky, and the completely mixed and cooled

mass is next placed directly against a pair of wet iron rolls and rolled out into a sheet form thereby. These rolls are continuously sprayed by water from both sides, so that they are maintained in a wet condition, and the water cooled mass of tar and felt can be readily rolled out into a thin sheet by these wet rolls without danger of the material sticking to the rolls. By adjusting the distance between the rolls a sheet of any desired thickness can be obtained.

Having thus described the invention, what I claim as new and desire to secure by Letters Patent, is:—

1. The process of making sheet material of the character described, which consists in melting a tar binder by the action of heat, thoroughly mixing a sufficient quantity of fibrous filling material with the tar binder to partially absorb the same, cooling the mass by subjecting it to a water bath, and rolling the cooled mass into a sheet between wet rolls.

2. The process of making sheet material of the character described, which consists in melting a tar binder by subjecting the same to the action of heat, stirring a sufficient quantity of fibrous filling material into the melted tar material to substantially absorb the same, cooling the hot mixture by subjecting it to a water bath, passing the cooled mass between iron rolls, and continuously spraying the rolls to prevent the mass from sticking thereto.

In testimony whereof I have signed my name to this specification in the presence of two subscribing witnesses.

LYMAN O. PICKETT.
